[57] CLAIM

The ornamental design for a wireless pay phone, as shown and described.

DESCRIPTION

FIG. 1 is a perspective view showing the front, upper and right side of the present invention;

FIG. 2 is a right side elevational view of the invention shown in FIG. 1;

FIG. 3 is a left side elevational view of the invention shown in FIG. 1;

FIG. 4 is a front elevational view of the invention shown in FIG. 1;

FIG. 5 is a top elevational view of the invention shown in FIG. 1;

FIG. 6 is a bottom elevational view of the invention shown in FIG. 1;

FIG. 7 is a perspective view showing the front, upper and right side of an alternate embodiment of the present invention;

FIG. 8 is a right side elevational view of the alternate embodiment of the present invention shown in FIG. 7;

FIG. 9 is a left side elevational view of the alternate embodiment of the present invention shown in FIG. 7;

FIG. 10 is a front elevational view of the alternate embodiment of the present invention shown in FIG. 7;

FIG. 11 is a top elevational view of the alternate embodiment of the present invention shown in FIG. 7; and,

FIG. 12 is a bottom elevational view of the alternate embodiment of the present invention shown in FIG. 7.
